UNITED STATES PATENT OFFICE

2,641,973

MACHINE FOR MAKING PAPER BOXES

Clayton Straw, Henniker, N. H., assignor to Henry
Russell Davis, Jr., Winchester, Mass.

Application September 15, 1945, Serial No. 616,506

27 Claims. (Cl. 93—41)

1

This invention relates to paper box forming and staying machines, and comprises a further application of the principles of my Patent No. 2,367,698, granted January 23, 1945, such patent setting forth a heat-activated stay material and methods and apparatus for applying the same to the corners of paper boxes in the process of forming the boxes.

A leading object of the present invention is to provide an improved and wholly automatic machine for setting up flat box blanks into box form and applying to all four corners thereof simultaneously the novel heat-activated stay material of my above patent, capable of utilizing the advantages of my novel stay strip to attain a production far higher than staying machines of any prior type.

Another leading object of the invention is to simplify and speed up the task of adjusting a quadruple-staying machine to make a different size of box. Prior commercial quadruple-staying machines take from 20 to 45 minutes of work in the process of setting them to make a different size of box, seriously impairing the economies of the automatic machine and thus requiring a big run of boxes to pay for the change-over alone, as in smaller runs it is cheaper to use hand-fed single-stay machines. The new machine of the invention can be set for any size of box within its range in a matter of 5 or 6 minutes, thus extending the economies of the automatic machine to a new field of small orders and short runs.

A further leading object is to provide an automatic quadruple-staying machine capable of making very small boxes, as on the order of one inch square. Since no automatic machine capable of making boxes of this size has been hitherto available to my knowledge, such boxes have had to be bent up by hand and also stayed by hand, if stayed at all. On account of the cost, they are commonly left unstayed, and wrapped on a wrapping machine of which the production is limited to from 900 to 1200 boxes per hour of this size, because the operator has to hold each box in shape until the wrapping machine takes hold of it. With these small boxes set up and stayed automatically by my novel machine, this assistance by the operator is not needed, since the stays hold the box in shape, and the wrapping machine can be fed and run faster, while producing boxes having superior strength because stayed. Additionally, with a production of around 10,000 boxes of this size per hour, my new machine will supply 6 to 8 wrapping machines even when the latter are run at increased speeds.

Other objects of the invention include a comprehensive reorganization of the stay feeding and applying devices which have been the main source of trouble in the operation of staying machines throughout their history, with special attention to improvements in the action of the presser to insure proper adhesion of the stay to the box; in the threading up of the stay strip in the machine and the entry of such strip into proper starting position; in the prevention of the heat of the presser from pre-activating the heat-responsive adhesive on the stay strip; in rendering the stay-cutting devices easily accessible for sharpening and adjusting; and through providing a fool-proof mechanism for varying the length of stay feed.

A further object is to improve the blank-feeding mechanism so as to reduce the travel of the blanks from the hopper to the form, which is of special importance in making small boxes, and to provide continuous mechanical control of the blank until positioned beneath the form, to provide for variation of the speed of transport of the blank in proportion to its size, and to preserve the proper timing of the blank feeding devices with respect to the other parts of the machine automatically and without need for hand adjustment when the length of box blank is changed.

Still further objects are to provide a mechanical take-out for the boxes timing their discharge from the machine accurately so as to synchronize with attachments or other machines performing further operations on the boxes, and to make this take-out easily removable when not needed or in the way.

Another object is to provide an improved give-way automatically disconnecting the form from its drive, to prevent breakage upon occurrence of a jam.

Other objects of the invention, and the manner of attainment of these and the aims detailed above, are as set forth in the following description.

An illustrative embodiment of the invention is shown in the accompanying drawings in which

Fig. 1 is a side elevation.

Fig. 2 is an end elevation.

Fig. 3 is a top plan view with certain parts removed, showing the stay feeding devices, their supports and drives.

Fig. 4 is a plan view of one stay feeder, on a larger scale.

Fig. 4^a is a face view of one of the tongued washers driving the stay feeder from its shaft.

Fig. 5 is an end elevation of the said feeder of Fig. 4, looking along the axis of the feed roll, showing the mounting of the idler roll and the stay guide.

Fig. 5a is a plan view of a stay-moistening attachment.

Fig. 6 is a side elevation of one of the reduction gear units for driving the splined shaft actuating the stay feeders at one side of the machine.

Fig. 7 is a plan view corresponding to Fig. 3, with the stay feeders and their supports removed to show the actuation of the corner pressers.

Fig. 8 is a side elevation of certain of the parts shown in Fig. 7 together with the form and the side-bending rails, and the means for adjusting the machine for different lengths of boxes.

Fig. 9 is an enlarged side elevation of the parts at the left-hand end of Fig. 8.

Fig. 10 is a perspective view of one of the novel heated corner pressers.

Fig. 11 is an end elevation showing the provisions for adjusting widthwise of the machine the rails carrying the corner blocks.

Fig. 12 is a section on line 12-12 of Fig. 11.

Fig. 13 shows the give-way connection between the plunger carrying the form and the yoke which actuates the plunger.

Figs. 14 and 15 are face and side views respectively of a transmission unit through which the stay feeders are actuated, and providing for hand feed of the stay material in starting up.

Fig. 16 is a view in axial section on line 16-16 of Fig. 17 of the stay feed length-control device.

Fig. 17 is an end view of the same.

Fig. 18 is a plan view of the manner of driving the parts applying pressure to the corners of the box and the reciprocating cross-head carrying the plunger up and down.

Fig. 19 shows in side elevation the blank feeder in its relation to the corner guides and the form.

Fig. 20 is an end elevation of the blank feeder showing the drives for the blank feed rolls and the adjustment of the lateral guide walls of the blank hopper.

Fig. 21 is an end elevation showing certain details of the blank feeder.

Fig. 22 shows the mechanical take-out applied to the side folders.

Fig. 23 shows the drive for the parallel shafts actuating the take-out.

Fig. 24 is a plan view on an enlarged scale of the lower left-hand corner block and corner presser of Fig. 7.

Fig. 25 is an end elevation of the parts of Fig. 24.

Fig. 26 is a detail on enlarged scale showing in elevation the feeder-slide and its associated parts and the drive therefor.

Fig. 27 is a detail showing in end elevation certain of the parts of Fig. 26.

Frame and drive features

The frame of the new machine is a housing 1 which is supported on feet or rails 3 and which is completely closed on all sides except at the central area of the top and at one end where an aperture is left for the discharge of the set-up boxes by means of a conveyor belt 5 running around a spring-biased idler 7 and a corresponding driving roll within the housing. A motor 9 is mounted on the outside of the housing by a suitable bracket and by means of a belt and pulleys 11 and 13 drives a jackshaft 15 having a pinion 17 driving a larger gear 19 on the main shaft 21 of the machine, the jackshaft being car-

ried in a flanged bracket 23 closing an aperture in housing 1 and having both of the necessary bearings for such shaft. Shaft 21 is mounted in anti-friction bearings in capped hubs 25 having flanges bolted over and closing apertures in the housing, one of such apertures being large enough to admit all the parts mounted on shaft 21. A face cam 27 is fixed on shaft 21 near each end thereof, and drives cross-head 29 carrying plunger 31 and form 33 thereon up and down as heretofore by means of rods 35 and arms 37 linked to the lower end thereof, the arms being pivoted at 39 to bosses on the inside of the housing and equipped with cam followers 41 working in the paths formed in the faces of cams 27.

The lower half of the base of the machine, shown as slightly enlarged over the dimensions of the upper half in Fig. 1, is a closed chamber or sump partly filled with oil in which run the gears and cams just referred to, the top being closed by a division sheet or baffle 38 except for passages formed in the latter for the chain 247 and slots permitting the pressure lever 51 to move back and forth, this division sheet keeping the fragments of broken blanks, stays, and other substances from falling into the oil in the sump. On this division sheet 38 are supported housings 40 holding the lower bearings for the plunger shafts 35.

Actuation of the stay-affixing means

At midlength of main shaft 21 is fixed an eccentric 43 surrounded by a strap 45 having an integral threaded shank 47 terminating in a portion of rectangular section fitting into a fork 48 at the lower end of pressure lever 51 and connected to the fork by a pivot pin. A heavy spring 53 around shank 47 bears against a shoulder 52 on a sleeve slideable on shank 47 and equipped with lugs 49 having round holes through which the pivot pin also passes. The hole in the shank 47 for the pin is in the form of a longitudinal slot, providing lost motion, so that the motion of shank 47 derived from eccentric 43 is imparted yielding to pressure lever 51 through spring 53, the degree of this pressure being adjustable by shifting a collar 55, screwed onto shank 47, lengthwise of the shank to stress or relax spring 53.

Pressure lever 51 is apertured as heretofore in certain instances, as shown in Fig. 2, to permit the take-out belt 5 to be extended clear through the front end of the machine if desired, to make possible the use of additional devices (not shown) for the applying of extension edges, cellophane windows, etc., to the boxes as they descend from the form.

The pressure lever 51 is mounted on a rock-shaft 57 held in bearings in connection with the side frames of the machine, the hub of the pressure lever being split and clamped as well as keyed to a large-diameter central portion of the rockshaft. At each side of this central portion, the rockshaft is reduced in diameter and provided with a plurality of flutes 59, Fig. 9, to provide for width adjustment of two arms 61 which in effect are the upper ends of the pressure lever. The hubs of these arms are provided with keyways to receive the flutes 59, Figs. 1 and 9, and the arms work in slots in the ends of the two rails 63 supported on main table 64, Fig. 7 (which is the plate forming the top of the machine and apertured at its center) so that their position is adjusted by the shift of these rails 75 in widening and narrowing the machine, being

thereafter fixed by clamp-screws 62, table 64 being also slotted to accommodate each arm 61. The upper ends of these arms 61 are each connected by a connecting link 65, Figs. 7 and 9, and wrist pins to a cylindrical member 67 which works like a piston in a cylindrical guide 69 fixed on each rail 63, the inward end of each piston being bored out to receive the enlarged end or head 71 of the pressure screw 73 for each rail, the head being retained by a sleeve-nut 75 threaded into the inside of the bore which receives the head 71. By this means, the necessary rotation of the pressure screws 73 needed to accommodate the changed position of the corner pressers to adapt the machine to a different size of box, as referred to hereinafter, is provided for, while any play in the connection between the piston 67 and the pressure screw is removed after the change is made by re-tightening sleeve-nut 75 to seat the head 71 tightly in the piston.

The pressure screws 73 serve by their endwise reciprocation derived from pressure levers 51, 61, to actuate racks 77, Figs. 7, 24, and 25, which transmit motion through intervening pinions 79 to racks 81 formed on the sides of the shanks of the diagonally disposed corner pressers 83 slidably mounted in guideways in each of the four corner blocks 85, thus thrusting the corner pressers 83 inward to set the stays across the corners of the box. The purpose in making the pressure screws as screws instead of as plain rods is to keep the starting and stopping points of the stroke of the corner pressers 83 constant automatically at all settings of the machine, thus eliminating a most troublesome and time-consuming manual adjustment operation hitherto required each time a machine of this type was reset to make a different size of box. Thus each pressure screw 73 is provided with a right-hand thread where it extends through one corner block 85 and a left-hand thread where it passes through the adjacent corner block 85, and each rack 77 is formed on the side of a member 87 in dovetailed sliding engagement with the corner block, Fig. 25, the member 87 being formed with a trough 89, Fig. 24, fitting freely about the threads of screw 73 but with a central section 91 which is constricted and carried upwardly and split along the line of the axis of the screw and equipped with a clamping screw 93, as well as being internally threaded to fit the thread on screw 73. In widening or narrowing the machine, therefore, after loosening sleeve-nuts 75 and clamp-screws 93 all round, the simultaneous and equal rotation of both pressure screws 73, produced incidentally to the shifting of corner blocks 85 to the new position, by means to be described later, automatically locates the racks 77 in proper position in the length of pressure screws 73 to maintain the proper starting point, stroke and pressure of corner pressers 83 when the operation of the machine is resumed, while affording a non-slip connection between the racks 77 and the driving elements 13. Thus the actual effect of this arrangement is to prevent relative movement between the corner pressers and their supports during movement of the supports in the process of adjusting the machine to make a different size of box. This relationship is then maintained by re-tightening clamp screws 93 and sleeve-nuts 75 to prevent further rotation of screws 73, and its attainment requires the exercise of no care or time other than the loosening and tightening of these parts.

A feature of the novel combination of the two

racks 77, 81, and the intervening pinion 79 is its low-loss transmission of the power from the pressure lever to the corner pressers 83, due to the fact that the thrust of the driving racks 77 is transmitted to the pinions 79, and thence from the pinions to the racks 81 on the presser shanks, at the most favorable angle, i. e., at right angles to the surfaces which are in mutual engagement, under all circumstances. With the pinion 79 mounted on anti-friction bearings 95 on studs 97, the latter being fixed in covers 99 applied to the pinion housing 101, the transmission loss from the pressure lever clear to the corner of the box is negligible. This overcomes the extremely wasteful loss of power which resulted in prior structures from driving the corner pressers solely by cams and followers, in order to transmit the power diagonally at the necessary 45° angle.

Adjustment for length of box

Rotation of the pressure screws 73 automatically in the act of changing the position of the corner blocks 85 is effected by means of a pinion 103, Figs. 8 and 9, fixed by a set screw on each pressure screw 73 adjacent sleeve-nut 75, meshing with a wide faced idler gear 105 which is driven by a pinion 107 on a table screw 109 having right and left-hand threads identical with those on screws 73 and extending between the rails 63 on which each associated pair of corner blocks 85 slides toward and from each other. Each table screw 109 is mounted for rotation in suitable bearings in connection with cylinder 69 at one end and with main table 64 at its other end, is rotated by a hand-crank 113 at the delivery end of the machine, and has its right and left-hand threads respectively engaged with nuts 115, Fig. 25, fixed on depending lugs 117 bolted to the outward ends of corner blocks 85. Thus when crank 113 is manipulated to move corner blocks 85 of each rail 63 toward or from each other, a corresponding rotation of pressure screws 73 ensues which causes racks 77 to shift their positions along pressure screws 73 a distance exactly equaling the shift of corner blocks 85, so as to cause the corner pressers to maintain the same working position in the corner blocks at all settings, clamping-screws 93 having of course been loosened.

Pressure screws 73 have to be made in two parts, joined at midlength of the machine, in order to get the two reversely threaded rack members 87 for the respective corner pressers into place thereon. For this purpose, the opposing ends of the two halves of each screw are threaded with the same thread, and joined by screwing into an internally threaded coupling 74, jam nuts being provided at each side of the coupling. This connection makes it possible to shift one-half of the pressure screw angularly on its axis with respect to the other half, to adjust the two corner pressers into exactly corresponding position on their corner blocks in erecting the machine.

In order to center the two corner blocks on each table screw 109 accurately with respect to the form 33 so that the middle line of each corner presser will exactly bi-sect the angle of the form and of the box against which it bears, adjustment of screw 109 within its pinion 107 is provided, the pinion being mounted against a shoulder on the shaft and held thereagainst by a sleeve 119, Fig. 9, a washer bearing against the end of the sleeve, and a nut 121 on the reduced and threaded extremity of the screw, the outside

of the sleeve 119 forming the bearing surface for the screw and working within a lug extending down from the casting which forms the cylinder 69, fixed on rail 63. Thus, by loosening nut 121 the screw can be rotated within nuts 115 on the corner blocks, which accomplishes the traverse of the corner blocks, and is for the moment employed to locate the associated corner block at the left-hand end of the machine accurately to the form. Then the other corner block is adjusted into symmetrical relation with the form by rotating its nut 115, Fig. 25, with respect to the pendent lug 117 whereby it is mounted on such corner block, this nut being externally threaded into the lug with a screw thread of opposite hand to the internal thread of such nut, so that rotation of the nut within its lug advances the corner block along screw 109 without any accompanying rotation of the latter screw. Then nut 115 is retained in adjusted relation by a screw 116 put through notches in the flange of the nut and into lug 117.

Side and end folders and blank guides

Each corner block 85 has two upstanding plates or folding members 123 disposed at right angles to each other. The plate of each corner block which is disposed transversely or at right angles to rails 63 has a small horizontal bracket 125, Figs. 22 and 25, fixed to its top end, in which bracket is a dove-tailed slot. In these slots of the respective plates of the two associated corner blocks mounted on each rail 63 is located a member 127 of dove-tail section on which is fixedly mounted a guide plate 129, Figs. 8 and 22, which with its supporting member 127 forms a bending rail, the plate being equipped with edge-guides 131 engaging the sides of the blank as fed under the form, so that each guide plate 129 is supported by two uprights, the plates 123 on each of the two corner blocks of that side of the machine. The dove-tail member 127 is adjustably fixed in one of its two brackets 125 by forming one side of the dove-tail in such bracket as a separate piece 133 clamped against the side of the member by a screw, while the member slides freely in the other bracket, so that the guide plate 129 will normally be in proper relation to its two corner blocks and the form without separate adjustment, as the two corner blocks are moved together or apart in narrowing or widening the machine. As the form descends on a blank resting on plates 129, the side flaps of the blank are folded upward, and the inward edges of plates 123 hold the flaps in this position as the form continues its downward course.

The four end-folders 123 which are disposed parallel to rails 63 are lower than those just described, have no guide plates or other parts, but engage the end flaps of the blank to bend them up across the ends of the form 33 after guide plates 129 have done so with the side flaps of the blank. It is noted that the inward working edges of all eight of these upright folding members have a relatively long upward and outward bevel 130, Fig. 25, at their top ends, which prolongs the folding action they perform on the sides of the box throughout a longer part of the descent of the form, which at the high speed of operation with which the boxes are set up and stayed in the present machine serves to prevent the breaking of the sides away from the bottom of the box along the score line between these parts, since the folding-up of the sides and ends is thus caused to take place more gradually.

The shape of these side and end folders 123 permits the corner blocks 85 to be set very close together, and thus permits the machine to be closed up to permit the making of very small boxes.

Width adjustment

The width-adjustment of the two rails 63 on which the paired corner blocks move lengthwise as described, is shown in Figs. 7, 11 and 12. Right and left-handed screws 145, made in two halves joined together at midlength, and one thereof rotated by hand-crank 147, and connected by chain 148 and sprockets fixed on the respective screws so that both screws turn in unison, pass through nuts 149 each having an integral fin 151 passing through a guide-slot 153 in main table 64 and into a close-fitting slot cut into the under side of the web of each rail 63. A dowel pin 157 connects the rail and the upper end of the fin 151 to prevent relative movement transversely of the rail. Bolts 159 pass through a strap 161 which takes bearing against the under side of the fin 151 on nut 149 to clamp the latter against the under side of table 64 and accordingly to clamp the rail against the top of table 64, after the width-adjustment has been attained by rotation of screws 145. Loosening of the nut 163 on the accessible outward side of each rail lets the strap 161 down to release the clamping pressure of the nut and rail against the top side of the table 64, so that the rotation of screws 145 will move the two rails simultaneously inward or outward. The connection between the right-hand and the left-hand halves of screw 145 permits of relative angular rotation to set the two tracks equidistant from the center point of the machine, in setting it up.

The stay-affixing devices

40 The heated pressers 83, Figs. 10 and 24, working diagonally in the corner blocks cut off appropriate lengths of stay material coated on one side with heat-activated adhesive and press them into position across the corners of the box while 45 simultaneously with such pressure activating the thermoplastic adhesive to cause the stays to adhere to the two sides of the box. These pressers are of novel construction, the head containing the reentrant right dihedral angle being prolonged vertically for about twice the vertical height of the shank, this head having heating means preferably in the form of an electrical resistance type heating element 135 embedded therein and extending from near the top to the bottom of the 50 head, centrally disposed in the head parallel to and quite near the inner corner of the reentrant angle, and supplied with current from a suitable source via flexible wires 137. Instead of having a rigid shank, the novel presser has a portion of its shank, extending from near the 55 head to the rack portion 81, made up of a plurality of strips 139 of spring steel arranged in vertical planes in spaced and parallel relation to each other, so that the head of the presser is 60 flexibly connected and able to swing in a horizontal plane and to twist as needed to effect accurate conformation to the surfaces of the box at each side of the corner, thereby getting equal pressure on the parts of the stay which are applied to the respective two sides of the box adjacent the corner. A suitable construction comprises the rabbetting and slotting of a short portion of shank formed integrally with the head of the presser, and a similar formation of the 65 proximate end of the solid tail portion of the

shank in which rack 81 is formed, with the strips 139 of spring steel fixed in the rabbets and slots by rivets 141. A further advantage of thus making a substantial portion of the length of the presser shank of these spaced spring steel strips is that this openwork construction gives an extended radiation surface and permits a free flow of air between the adjacent strips, thus serving to dissipate the heat flowing back along the shank from the head and obstructing its flow to the adjacent parts of the machine whence it might get to the stay-handling devices and activate the stay prematurely, which might interfere with the proper operation of the machine. For the same purpose of obstructing the heat flow to the machine parts, the sides of the guideway in each corner block adjacent the head of the presser are lined with heat insulating material 143, Figs. 7 and 24, such as hard pressed asbestos board. Stationary stay-cutting blade 144, Fig. 5, fixed to the top of corner block 85, intervenes between the top surface of the head of the presser and the parts of the stay-feeder overlying this presser, shielding them from the heat.

The devices for feeding the thermoplastic stay strip include a shaft 165, Figs. 1 and 3, running across the machine at the delivery end thereof, this shaft running through two gear boxes 167 bolted on the ends of the respective rails 63 at the delivery end of the machine. Shaft 165 is splined, and drives a spur gear 169, Fig. 6, in each gear box, through which gear the shaft 165 slides, this spur gear driving a smaller spur gear 171 and bevel gears 173 in connection therewith, all within the gear box, to rotate a stay-feed shaft 175 extending lengthwise of each rail. The gear ratio increases the angular rotation of the stay-feed shafts, so that a smaller ratio and more compact parts can be used to drive the shaft 165. Each driven bevel gear 173 has its hub extended out through the gear case and bored and slotted to form a socket receiving the end of its stay-feed shaft 175 and a pin extending radially from the end of such shaft, the parts being held in connection by a cap 177 which is screwed manually on the threaded exterior portion 179 of the bevel gear hub, making a coupling which can be quickly and easily released as one step in the novel provision for taking out the entire stay-feed organization associated with each rail when the time comes to sharpen the stay cutters.

Accessibility of stay-cutters

The sharpening and adjustment of the stay-cutters has hitherto been a laborious and time-consuming operation needing to be done every few weeks when the machine is in constant use, and has always required the practical dismantling of the entire mechanism connected with the stay-feeding and applying so that each cutter in turn could be removed and sharpened and could be operated manually while the cutters were being adjusted into proper relation when re-installed. With the aim of reducing the time and effort and nuisance to a minimum, the present stay-feeding mechanism has been contrived so that to effect removal it is necessary only to uncouple the two shafts 175 from their driving hubs by unscrewing the caps 177, and to remove the two cap screws 181 respectively holding the two stay-feed stands of Fig. 4 associated with each shaft 175 on their respective corner blocks 85. The entire stay-feed mechanisms are then lifted off by means of their shafts 175 as two units, leaving the moving cutter blades 183 completely ac-

cessible from above as illustrated in Fig. 7. As shown in Fig. 10, the moving cutter blades 183 are mounted directly on top of the corner pressers 83, each blade being affixed thereto by screws 184 with its V-shaped cutting edge in exact conformity with the right dihedral angle comprising the working face of the presser. The stationary blade 144, Fig. 5, is mounted on the corner block 85 directly over the movable blade, bridging the shank of the presser 83. By removing the retaining screws, the cutter blades 183 are quickly removed for resharpening or replaced. The cooperating stationary shearing blade 144, of usual construction and known spring-pressed type, against which the moving cutter blade 183 acts to shear off the desired length of stay, is also made completely accessible for re-sharpening, when the stands are taken off from their corner blocks. The particular advantage of the improved rotary type of stay feed employed herein is that quick replacement of the parts by reversing the steps required to remove them, is effected without need for readjustment when the parts are put back in place, as the pin in the end of each shaft 175 serves to index the shaft in reassembling and thus preserves the timed relation of the unit to the other machine parts while the stay-feeders stay on the shaft to preserve their driving relation thereto.

Form drive

In this connection, to make the pressers and the blades 144, 183 and other parts at the center of the machine more easily accessible, as well as to introduce a safety feature preventing breakage or springing of parts, a give-way connection shown in Figs. 1 and 13 is provided between the square plunger 31 carrying the form 33 and the reciprocating cross-head 29 which actuates it. For this purpose, plunger 31 is slidably mounted in a sleeve 32 of rectangular section which is held in operatively fixed position in a square seat in cross-head 29 by a flat clamping plate 34 applied to the cross-head by cap screws 36. A lug 38 is formed on plunger 31 near the top thereof, which is engaged from above by a detent 40 pivoted at 42 on a bracket forming a part of sleeve 32 and pressed downward on top of lug 38 by an expanding coil spring 44 confined between a seat 46 pivotally mounted on a lug on an arm 48 integral with the detent and a corresponding seat 50 forming a part of sleeve 32. By pressing down manually on the handle or arm 48 detent 40 is withdrawn from above lug 38 on the plunger, permitting the latter to be slid upward through sleeve 32 by manual pull on knob 52, thus lifting the form 33 up to the cross-head and giving free access to the region below the form. Detent 40 bears against the side of plunger 31 when handle 48 is released, to hold the plunger and form in lifted position out of the way while work is being performed beneath it. Thereafter, manual pressure on handle 48 retracts detent 40 to let the form and plunger descend until lug 38 rests on top of sleeve 32, whereupon release of the lever permits detent 40 to resume its position above lug 38 holding the latter in normal working position against sleeve 32. When any substantial obstruction to the descent of form 33 is met with in the course of the operation of the machine, detent 40 yields upwardly and moves away from plunger 31, permitting lug 38 to snap past it and allowing the descent of the form to be checked while cross-head 29 continues to descend, thus preventing any breakage of parts.

This mechanism also provides for very accurate adjustment of the spaced relation of the form with respect to the cross-head, to fix the exact extent of downward travel of the form, by means of a thumb screw 54 having an unthreaded shank received in a cavity formed in cross-head 29 and seating against the bottom of such cavity, and an upwardly extending threaded shank in screw-engagement with a lug 56 integral with sleeve 32. Thus, when screws 36 of clamping plate 34 are loosened, screw 54 is turned one way or the other to raise sleeve 32 or to let it down with respect to cross-head 29, thus raising or lowering the form relative to the latter, the adjustment being maintained by retightening of screws 36.

This adjustment is used to adjust the descent of the form to suit the depth of box being made thereon. By raising or lowering the form thereby, with respect to the cross-head 29, the cutting off of the stay in proper relation to the top edge of the box is accomplished.

The stay feed

Each of the four stay-feeders, as shown in Fig. 4, comprises a bevel gear 185 having a hub 187 rotating in a collar 191 forming a part of the stay-feeder stand 193, the end of the hub being slotted at 195 and externally threaded and a plurality of tongued washers 189, Fig. 4a, being slipped over the projecting end of the hub to seat against the collar 191, so that their tongues project through the slots 195 and into grooves 197 in stay-feed shaft 175 which extends through the hub of bevel gear 185. A jam-nut 199 is applied to the threaded end of the hub outside the washers to hold them on the hub.

Bevel gear 185 meshes with a companion bevel gear 201 pivotally mounted at 45° to the first one upon a stud 203 fixed in stand 193. Bevel gear 201 is formed as an integral part of a knurled stay-feed roller 205, with which an idler roll 207 cooperates to press the stay between them to insure the movement of the stay in exact unison with the travel of the knurled surface of feed-roll 205. This idler roll is yieldingly pressed against the surface of the feed-roll so as to keep a constant pressure on the stay, and is shiftable away from the feed-roll for convenience in threading up and in clearing jams. For this purpose, feed-roll 207 is mounted on a stud 209 which is fixed in an arm 211 on an eccentric strap 212 rotatably mounted on an eccentric 215 which is mounted on the projecting end of stud 203, the angular position of the eccentric being fixed by a screw 217 put through a slot 213 in the eccentric and into stand 193. The eccentric strap 212 is constantly urged counterclockwise by an expanding spring 219 confined between the base of stand 193 and a lug 221 on the side of the strap, thus rotating the strap in a direction which brings the idler roll 207 yieldingly toward the surface of feed-roll 205 to press the intervening stay strip against the knurled surface of the latter, the center of rotation of the strap 212 about eccentric 215 being apart from the axis of feed-roll 205.

The arm 211 of eccentric strap 212 which carries idler roll 207 has an integral or otherwise rigid extension 223 which extends laterally and then vertically downward just outside the path of the form, so that the surface of such extension which is toward feed-roll 205 guides the stay fed between the two rolls downwardly through a cutting slot in stationary cutter 144 and into parallel with the corner of the box, thus bringing the stay into position across the face of corner presser 83. The

described arrangement of the eccentric makes it possible to keep this guide device always in vertical relation, so that it will not obstruct the descent of the box, its clearance from the descending form being very close to this point, yet at the same time the guide can be swung inward and upward of the machine so that the operator can get his fingers between it and the feed-roll to clear out doubled-up stay when a jam occurs. The arrangement of the eccentric thus provides for keeping the angle of guide 223 on the eccentric strap always the same, so that the guide will be vertical, in spite of wear of the idler roll and its bearings which would otherwise permit this angle to change. As a fixed mounting for the idler roll and guide surface cannot be employed since both must be swung out of the way for threading up and clearing jams, the improved construction both provides for this necessary movement and also by separating the idler roll and the guide and spacing them apart from each other in the length of the stay, avoids the previous serious difficulty, resulting from having the idler roll work through a slot in the guide, of having the slot eventually choke up with paper fibers and adhesive and stop the roll's rotation, causing a flat place to wear on the tread of the idler roll destroying its further utility and requiring its replacement.

Stay feed drive

The transverse shaft 165 which drives the stay-feeding shafts 175 is itself driven through a double roller ratchet 225, Fig. 15, or Horton clutch, so-called, from multiplying gears 226, 227, Fig. 14, actuated by an obliquely disposed rack 229 in a housing 231 affixed at 233 to the inside of one side frame of the machine. The internal hub 235 of the roller ratchet is fixed on the end of transverse shaft 165, with one set of rollers working inside the flange of a spur gear 228 of the multiplying gear train, such spur gear being loose on shaft 165, while the other set of rollers 223 on the same hub 235 engages within the rim of a cup 239 fixed to the inside of housing 231, with the result that when the spur gear 226 is rotated in one direction by the movement of rack 229 it imparts its rotation to the shaft, but when the gear moves reversely the gear ratchet releases and the cup ratchet holds the shaft from reversal of its direction of rotation. With this arrangement, a hand-wheel 241 fixed on the extreme end of the shaft outside of the housing enables the mechanism to be actuated by hand to feed the stay through the feeders in starting up the machine and in testing and adjusting the length of stay fed.

To actuate the rack, it is connected at 243 with a connecting rod 245, Figs. 1 and 14, which is pivoted on a crank pin 257 on a constantly rotating member driven by suitable chains 247 and sprockets from the main shaft 21.

Stay feed adjustment

To adjust the length of stay fed at each actuation, the throw of this crank pin is varied. The mechanism providing for this is shown in Fig. 16, and comprises a sleeve 249 constantly driven by a sprocket 251, actuated by one of the chains 247, offset from its hub on account of the necessities of the location of the distant sprocket driving the chain which actuates this sleeve. The latter sleeve has an inner end of enlarged diameter, in which is formed a diametric dove-tailed slot 253, with a correspondingly dove-tailed block 255 sliding therein and formed with an integral crank pin 257 which goes through the eye in the end

of connecting rod 245. To adjust the eccentricity of this crank pin, and hence the throw of rack 229, block 255 has a transverse slot 258 in which works an eccentrically located pin 259 fixed in the inner end of a tubular member 261 which rotates within the interior passage of sleeve 249 and has fixed on its outward end an indicating pointer 263. The sleeve 249 has a recessed dial 265 affixed to its outward end by screws 268, such dial being inscribed with numbered indexing marks or divisions as shown in Fig. 17, against which the pointer 263 works. Thus rotation of the tubular member 261 to which the pointer is attached, relative to the sleeve 249 having the dove-tailed slot, slides the dove-tailed part 255 carrying the crank pin 257 along the slot 253, changing the eccentricity of the crank pin 257 and thus the throw of the crank and rack 229 to a known degree as indicated by the scale on dial 265. After the desired crank throw and resulting length of stay feed has been attained, the parts are locked in adjusted position by tightening a long screw 267 equipped with a head 269 and which is threaded into the reduced inner end of the passage through tubular member 261, the end of such screw pressing against a washer 271 slipped over pin 259 and interposed between the end of tubular member 261 and the part 255 to bridge the slot 258 in the latter, and hold the part 255 in fixed position in the dove-tailed slot 253 without any strain on the adjusting mechanism. To mount this adjusting device rotatably in the machine, the sleeve member 249 rotates in a bearing 273 affixed by screws passing through lugs 274 in its flange to the outside of one side frame of the machine.

It will be seen that the improved adjusting device makes it mechanically impossible for an unwary operator to set the parts on dead center in a relationship in which breakage of the parts will result when the machine is started up, as frequently occurred in prior structures. Over-adjustment of the pointer past the end of the scale simply results in bringing crank pin 257 back toward its center of revolution, reducing the throw of the crank and avoiding all damage to the working parts.

Alternative use of glue-coated stay

The improved stay-feeding devices, though primarily designed for the feeding of thermoplastic stay with its freedom from troubles incident to gumming-up of the stay-feeding and handling devices and immunity from difficulties arising through faulty adhesion and changing atmospheric conditions, is still easily adaptable to the use of the older stay material coated with glue or other water-activated adhesive. In using either type of stay, the roll of stay strip supplying each of the four stay feeders is mounted for unwinding rotation in any usual or preferred manner adjacent each corner block. When stay strip having water-activated adhesive is used, the moistening unit 279, Fig. 5a, is mounted on each corner block as indicated in dotted lines on the upper right-hand corner block of Fig. 3, and the usual conditioning roll 275 mounted in a slot in an arm 277 on each corner block 85 is employed to lengthen the path from such unit to the stay feeder. Water is kept in the reservoir 281 into which dips a large moistening roll 283, the advancing stay strip being led under a guide-roll 285 and over roll 283 to rotate the latter. The moistening roll has the usual groove in the middle of its face, so as to leave a narrow strip of unmoistened adhesive in the zone where idler roll 75 passing through the aperture 291 in main table

207 presses the strip against feed-roll 205, to reduce the gumming-up of the knurled surface of the feed-roll. Otherwise, the parts and operations used in employing wetted stay strip are the same as in using thermoplastic stay material, the pressers being kept heated to speed up the adhesion of the wetted stay to the box corners and thus enabling the machine to be run at a higher rate of production.

10

Blank-feeding devices

Improvements in the blank-feeding devices with the objects set forth in the preamble hereof include the mounting of the feeding devices on the main table so as to be adjustable as a unit toward and from the path of the form. For this purpose, the hopper 287, Figs. 1, 19, 20, 21, has its bottom 289 slidably mounted by means of a heavy rib 291 on its under side in guides 293 on the top edges of a box-like housing or stand 295, Fig. 19, attached by cap screws 296 to main table 64 over an aperture 297 cut in table 64 at the middle of its width. In this housing is fixed a vertical plate 299, Figs. 19 and 21, stretching across the interior of the housing and fixed in place by cap screws 298 put through the side walls of the housing into the plate 299. A bracket 301 fixed on the end of hopper bottom 289 carries a screw 303 which is threaded through fixed plate 299, the screw being prevented from endwise movement in bracket 301 so that manual rotation of the screw by handle 305 advances or retracts the hopper as a unit toward and from the path of the form 33. The hopper has an end-plate 307 which is supported with its lower edge above hopper bottom 289, by one short side wall 309 and one long side wall 311, both attached to the side edges of bottom 289, the latter side wall having a housing 379, Fig. 21, applied to its outward surface and serving as a guard for the actuating members of a blank pusher 365. End-wall 307 is provided with the usual gate comprising a member 313, Fig. 20, vertically adjustable in dove-tail guides in end-plate 307 so that its lower end may be spaced accurately from end-wall 315, Fig. 19, by a distance exactly equaling the thickness of the blanks to be fed, so as to permit only one blank at a time to be fed forward from the bottom of a stack of blanks lying with their leading edges against the inward surface of end-plate 307.

To feed the blanks one by one from the bottom of the stack along the hopper bottom and through the gate, a feeder-slide 317, Figs. 21, 26, and 27, works in a T-slot cut longitudinally 55 along the center line of hopper bottom 289, the feeder-slide having a device 319 to slip under the stack and push the bottom blank through the gate. To actuate the feeder-slide, a cam-follower roll 321 is mounted on a pin fixed in a lug 322 integral with feeder-slide 317 and extending through a slot 323 cut through the heavy rib 291 of the hopper bottom below the T-slot therein. Follower-roll 321 works in a cam-groove or path 325 in a combined barrel and end-cam 327 fixed on a splined shaft 329 rotating in bearings 331 depending from the under side of rib 291. This shaft is driven by a sprocket 333 having a hub slotted to take the spline on the shaft, and held against endwise movement with the shaft as the hopper is adjusted forward or back from the form by fitting the reduced intermediate part of the hub into a slot formed in the top of plate 299 fixed in the housing 295. Sprocket 333 is driven by a chain 335 passing through the aperture 291 in main table

64 and through a registering opening in the plate 299, the chain being driven by a sprocket 337, Figs. 1 and 21, fixed on a jackshaft 339 mounted in suitable bearings in a baffle plate 341 extending across the interior of the machine from one side wall to the other. This jackshaft is driven by bevel gears from the transverse shaft 342 transmitting the drive from one chain 241 to the other chain 241 of the stay-feeding devices, previously referred to.

The actual feeding device 319, Figs. 26 and 27, is fixed to feeder-slide 317 with capacity for its adjustment lengthwise thereof to suit the length of blank being fed, by cutting a T-slot 343 lengthwise in the feeder-slide, and putting a screw 345 down through the member 319 into a rectangular block 347 occupying the wide part of this T-slot, the feeder device having a tongue which also fits into the upper portion of such T-slot to hold it against rotation on the feeder slide. After adjustment to the proper lengthwise position, tightening of the screw 345 causes the block to clamp against the overhanging sides of the slot and fix the device in the adjusted position. The top surface of feeding device 319 inclines upwardly and away from the end-plate 307 of the hopper and is equipped at its high end with thin metal plates 318 applied to its inclined surface which are of the exact thickness of the stock being used for the blanks, so that the lowermost blank in the stack will settle in front of them as this end of the feeding device passes out from under the stack, and on its next forward stroke this one blank alone will be fed from the bottom of the stack through the gate. The blanks are confined between end-plate 307 and a back-stop 349, Figs. 1 and 26, this back-stop having an upright part to engage the rearward edges of the stacked-up blanks and a foot at right angles thereto and of dove-tail section fitting within a dove-tail 351, Fig. 21, in the hopper bottom above the T-slot for the feeder-slide. The foot of the back-stop is split vertically and expanded to hold the foot in position after having been adjusted lengthwise of the hopper bottom to suit the length of the blanks, by tightening a wing-nut 353 on the shank of a screw put through the split and having a downwardly flaring head engaging the sides of the split.

The rear edge of the feeding device 319 is slotted so that the blank-grasping edges of the plates 318 can pass back of the working surface of back-stop 349, to ensure getting beyond the edge of the bottom blank and make sure this blank is slid out from under the stack by the plates 318 on the next forward movement of feeding device 319. When very small boxes are being made, the metal plates 318 are located near the front edge of the feeding device 319, and an extension 355 is mounted on the back-stop comprising a metal strip fixed to the top of the back-stop and extending forward and downward into proximity with the surface of feeding device 319, thus keeping the rear edge of the stack forward of the rearward position of these plates 318 while providing for a relatively longer useful part of the feeding stroke of the feeding device 319.

The function of the feeding device just described is to feed the blanks successively from the bottom of the stack through the gate and into the nip of a pair of feed rolls 357, 359. The actual travel of the leading edge of the blank from its starting point below the rearward surface of end-plate 307 until it is seized by the feed rolls is on the order of only 1½ inches, ensuring com-

plete control of the blank during this movement.

The top roll 357, Figs. 19 and 20, of the pair of feed rolls propelling the blank is divided into two entirely separate halves, which are respectively mounted on anti-friction bearings 360 on aligned stub-shafts 361 fixed in brackets 363 mounted on the front face of end-plate 307 of the hopper. This permits a blank-pusher 365 to swing back behind this divided roll to get back of the rearward edge of the blank being fed by the feed rolls before such blank has been released by the feed rolls, so that the pusher can take over the propulsion of this blank just as its rearward edge passes out from the nip of the upper and lower feed rolls, and thus maintain the positive mechanical control of the blank from the moment it starts forward beneath the stack and until it reaches its final position beneath the form 33. Bottom feed roll 359 is grooved as indicated at 367 also, so that the end of the pusher can extend below the level of the nip of the rolls and take over the feeding of the blank the instant it is released by the feed rolls.

To drive the two halves of the upper feed roll 357 in unison, a pinion gear 369 is fixed to the end of each half thereof, one of such gears being driven by a pinion 371 fixed on the end of a jack-shaft 373 driven by V-pulley 375 and V-belt 376 passing therearound, from a motor 377 mounted on a housing 379 on the outside of the long side wall 311 of the hopper, and extending for the full length thereof.

The drive for the other half of divided top roll 357 is carried up from driving pinion 371 to pinion 372, thence across via shaft 374 to pinion 376, and thence through idler 378 to the gear 369 fixed on the end of the other half of top feed roll 357, these parts being all supported by the brackets 363. The vertical spaced relation of cross-shaft 374 permits sufficient swing of the pusher 365 to let its lower end reach back of the nip line of the feed rolls.

The belt 376 also passes around a V-pulley 381 fixed on a jackshaft 383 mounted in bearings 384 on the under side of hopper bottom 289, the jackshaft driving a spur gear 385 which meshes with an idler gear 387 which in turn engages with gear 389 fixed on the end of bottom feed roll 359. The latter roll and its idler gear 387 are mounted in brackets 391 swinging around jackshaft 383 and suitably as by spring 392 to hold the bottom feed roll up to the top feed roll, but with capacity for yielding movement downward as the blank passes through.

Pusher 365 is an arm fixed by means of its hub on a rockshaft 393 working in a bearing 395 formed on a bracket 397 attached to the front wall of the end-plate 307. This rockshaft is actuated by a short arm 399 fixed on the rockshaft and connected by a link 401, Fig. 19, extending within the housing 379 where it is connected to an arm 403, Fig. 21, fixed on a rockshaft 405 working in a sleeve bearing 407 on the under side of hopper bottom 289. A bent arm 409 fixed on the other end of this rockshaft has a cam-follower roll 411 which is held against an end cam 413, Fig. 19, on barrel cam 321 by a pull spring 415 attached to link 401 within the housing 379 and anchored to a screw in side wall 311. Thus as the barrel cam revolves, pusher 365 is alternately swung positively toward the form to propel the box blank toward the form, and is swung yieldingly in the opposite direction to bring the pusher back beyond the nip of feed rolls 357, 359 for its next operation.

The working end of the pusher 365 swings in a path well below the nip-line of the two feed rolls, by virtue of the groove 361 in the lower feed roll, as already noted, and is timed by the angular adjustment of its end cam 413 when the machine is first set up so that it will just finish its working stroke and come to rest as the form 33 descends into contact with the blank, the pusher pushing the blank forward along guide rails 129, onto which it is fed by the feed rolls, and into position against adjustable stops 417, Fig. 19, on the end of adjusting screws, and holding the blank against rebound. Two of these stops 417 are provided, each located on one of the two end-folders 123 at the side of the path of the form which is remote from the hopper, each stop having swiveling connection with the end of an adjusting screw 419 threaded through an eye in a bracket 420 fixed on the top end of each member 123, these stops serving to center and square up the blank with respect to the form in the lengthwise direction of the machine.

To adjust the stroke of the pusher to a different length of box blank and a correspondingly different position of each stop 417, so that the box blank will neither be crumpled against the stops nor stop short of arrival thereat, no change is made in the length of the pusher's stroke regardless of the difference in blank sizes. Instead, the whole hopper is adjusted bodily toward or from the path of the form by the described single operation of turning the crank 395.

The virtue of this improved manner of operation is that no change in the timing of any part of the reciprocating feeding device or the pusher is needed in changing over the machine to a different size of box, and no risk of the loss of timing is incurred. This is in decided contrast with prior machines of this type in which the scope of movement of the pusher or other feeding devices has to be readjusted painstakingly for each different size of box being made. The saving in the time required for making the change-over is obvious and material.

The fact that the entire hopper is adjustable toward and from the path of the form makes possible a refinement which is of considerable advantage in high speed production. Not only does the present structure provide for shortening the path of small box blanks from the stack to the form, thus reducing the chance of a blank going astray in feeding, but also provides for reduction of the speed of propulsion of the blank itself by the feed rolls as the size of the boxes to be made decreases. Since the same proportion of the machine's cycle is available for feeding both large and small blanks, and since the rate of surface travel of the feed rolls 357 and 359 needed for feeding large box blanks is far in excess of that needed for feeding small box blanks, the speed of the feed rolls is reduced proportionately to the blank's length, thus making easier the attainment of the necessary accuracy of feed of these smaller blanks. For this purpose, the motor 377 driving the feed rolls is equipped with a speed control 421, Fig. 20, of standard or any preferred design, preferably of the electronic control type, for changing the speed of the motor and thus of the feed rolls.

The outstanding advantage of the whole blank feeding structure is that there is never any time when the blank is not under complete mechanical control from the time it starts to move under the bottom of the stack in the hopper to the moment when it is encountered by the descend-

ing form. From the moment the blank to be fed leaves the back-stop 349 it is successively and continuously engaged by at least one of the feeding devices, first the feeder 319, then the feed rolls 357, 359, then the pusher 365, and then the form 33; and throughout its movement the blank is supported from below successively by the bottom of the hopper, the lower feed roll, and the guide-bars 129, entering between side-guides 131 on the latter members before it is released by the feed rolls. At the instant the pusher brings the blank up against the adjustable stops 417 at the far side of the path of the form, the form engages the top surface of the blank and presses it against the top of the guide-bars 129, while the sides of the blank are held from deviation and the blank from rotation by the side-guides 131.

These novel provisions make it possible for the machine to operate on blanks of a size smaller than have hitherto been capable of being handled by an automatic box making machine.

Mechanical take-out

Fig. 22 shows the features of the mechanical take-out for discharging the finished boxes from the chute comprised by the side-folding and end-folding members in accurately and properly timed and spaced relation so as to synchronize with attachments (not shown) performing special operations on the boxes, as for example applying flanged bottoms, or with other machines performing further operations on the boxes, as where the boxes are of sufficiently large size to warrant being mechanically nested by a box stacker. In the absence of some such take-out mechanism, the boxes sometimes lag in the chute, and two or three will descend together. When the boxes are of very small size and thus do not admit of being nested, and are not to be additionally worked on by special attachments to the machine, the mechanical take-out is superfluous, and therefore is arranged to be removed easily when not needed. Thus, each of the four side-folders 123 respectively connected with the four corner blocks 85, and located at the longitudinal sides of the form, is replaced by side-folders 124 prolonged below the rails 63 and center frame as shown in Fig. 22 and carried well down toward the take-out belt 5, and equipped with a sprocket 423 rotatably mounted on a stud 425 fixed in the side-folder, and around this sprocket passes a take-out chain 427, equipped with carrier links having projections 429 to engage the top rims of the boxes and carry them down and out from the chute. The lower loop of the chain passes around a sprocket 431 mounted by means of its extended hub in a bearing adjustable up and down in the lower end of side-folder 124, the hub being retained by a collar on the end of the hub and such hub having an axial hexagonal passage therethrough to receive hexagonal shaft 433, Fig. 23, driving the two take-out chains located on each side of the path of the form. These shafts are each detachably held by one of their ends in a hexagonal socket in the hub of a bevel gear 435, being held in such socket by ball snaps for instant removal. The respective bevel gears are driven by other bevel gears 437 splined to a cross-shaft 439 provided with a long feather, each pair of bevel gears being enclosed in a housing 441 floating on cross-shaft 439, so that the housings and driver bevel gears will shift with the corner blocks in widening and narrowing the machine.

Cross-shaft 439 is driven by spur pinions 443, 445, at an increased speed from cross-shaft 342, Figs. 1, 21, and 23, feathered shaft 439 being carried in radius arms 447 swinging about the adjacent shaft 342 to permit lowering of the two hexagonal shafts 433 as needed in order to keep the take-out chains 427 tight in use. By this means all four take-out chains are driven in unison with their inward runs traveling in a downward direction and with their corresponding projections 428 moving in unison.

To remove the take-out mechanism when not needed, it is merely necessary to remove the single screw 449 which cooperates with a pair of pins fixed in the side of the corner block 85 to hold each long side-folder 124 in working position thereon, and then pull out each of the hexagonal shafts 433 from their sockets in bevel gears 435, whereupon each shaft with two of the side-folders borne thereon is taken out of the machine as a unit. The regular short side-folders 123 as illustrated in Fig. 25 extending only down to the bottoms of the corner blocks are then mounted to replace the long ones thus removed.

While I have illustrated and described certain forms in which the invention may be embodied, I am aware that many modifications may be made therein by any person skilled in the art, without departing from the scope of the invention as expressed in the claims. Therefore, I do not wish to be limited to the particular forms shown, or to the details of construction thereof, but

What I do claim is:

1. In a box-staying machine, in combination, corner pressers, a pair of shafts each operating two of such pressers, a rockshaft, spaced arms each pivotally connected to and imparting end-wise movement to one of the said presser shafts and in angularly fixed relation upon said rockshaft but freely slideable longitudinally thereon, and means rocking the rockshaft to actuate the corner pressers.

2. In a paper box-making machine, in combination, a frame, devices operating on box parts mounted on such frame, cam and gear means driving such devices and located beneath such devices, and an oil sump enclosing such driving means and having baffle means over its top excluding box fragments falling from the devices operating on the box parts.

3. In a box-staying machine, in combination, means setting up box blanks into box form, a corner presser diagonally disposed to the sides of the box being formed, and pressing stay material into adherence across a corner of such box, an actuating element reciprocating parallel to a side of the said box, racks on the corner presser and on the actuating element, and a pinion mutually engaging the respective racks transmitting motion from the actuating element directly to the corner presser to move it obliquely to the direction of movement of the actuating element.

4. In a box-staying machine, in combination, means setting up box blanks into box form, a corner presser diagonally disposed to the sides of the box being formed, and pressing stay material into adherence across a corner of such box, an actuating element reciprocating parallel to a side of the said box, racks on the corner presser and on the actuating element, a pinion mutually engaging the respective racks transmitting motion from the actuating element directly to the corner presser to move it obliquely to the

direction of movement of the actuating element, and means providing for shift of the racks on the actuating element bodily with respect to such element.

5. In a box-staying machine, in combination, means setting up box blanks into box form, a corner presser diagonally disposed to the sides of the box being formed, and pressing stay material into adherence across a corner of such box, an actuating element reciprocating parallel to a side of the said box, racks on the corner presser and on the actuating element, a pinion mutually engaging the respective racks transmitting motion from the actuating element directly to the corner presser to move it obliquely to the direction of movement of the actuating element, and means automatically shifting the rack on the actuating element bodily with respect to such element as the location of the corner presser is changed in adjusting the machine to a different size of box.

6. In a box-staying machine, in combination, means setting up box blanks into box form, a corner presser diagonally disposed to the sides of the box being formed, and pressing stay material into adherence across a corner of such box, an actuating element reciprocating in a course parallel to a side of the said box, and driving means transmitting the drive from such element to the corner presser maintaining positive mechanical driving connection in both directions of reciprocation between the parts, such element being in rotatable screw-threaded engagement with the driving means permitting shift of the working location of the corner presser in the directions of reciprocation without actuating the corner presser.

7. In a box-staying machine, in combination, means setting up box blanks into box form, corner pressers diagonally disposed to the sides of 40 to their supports to press the stay material into adherence across the corners of such box, supports for the corner pressers respectively movable toward and from each other to adjust the machine to a different size of box, reciprocating means moving the corner pressers relative to their supports to press the stay material against the box, and means preventing relative movement between the corner pressers and their supports during movement of the latter.

8. In a box-staying machine, in combination, means setting up box blanks into box form, corner pressers diagonally disposed to the sides of the box being formed, and pressing stay material into adherence across the corners of such box, a reciprocating rod, and driving means transmitting the drive from such rod to a corner presser, the rod being in screw-threaded engagement with the driving means permitting shift of the working location of the corner presser along the rod without change of the driving relation between the rod and the corner presser.

9. In a box-staying machine, in combination, means setting up box blanks into box form, corner pressers diagonally disposed to the sides of the box being formed, and pressing stay material into adherence across the corners of such box, supports for the corner pressers respectively movable toward and from each other to adjust the machine to a different size of box, a screw-threaded reciprocating rod, a rack slidably mounted on one of the supports and in screw-threaded engagement with the reciprocating rod, rack and pinion means transmitting reciprocation from the first rack to a corner presser, means shifting the support, and means rotating the rod

to shift the rack therealong a distance equalling the shift of the support.

10. In a box-staying machine, in combination, setting-up devices, corner pressers for each of the four corners of a rectangular box, a reciprocating screw-threaded rod, means transmitting a driving impulse from such rod to a corner presser including an element screwed onto the threaded rod, a movable support for the corner presser, screw means rotatable to shift the movable support in adjusting the machine to a different size of box, and means causing simultaneous rotation of the screw-threaded rod to produce an equal shift of the element of the drive-transmitting means along the said rod.

11. In a box-making machine, in combination, setting-up devices, corner pressers for each of the four corners of a rectangular box, two reciprocating elements moving parallel to a side of the box being made and each actuating two corner 20 pressers, and a single lever reciprocating both reciprocating elements.

12. In a box-making machine, in combination, setting-up devices, corner pressers, supports for the corner pressers, a rotatable shaft having both right and left hand screw threads thereon, a female screw element on each support engaging one of the screw threads and being propelled along the shaft as the latter rotates, and means mounting one of the female screw elements in operatively fixed relation on its support with capacity for angular adjustment about the axis of the screw.

13. In a box-making machine, in combination, a reciprocating form, corner pressers, supports for the pressers adjustable toward and from each other for different sizes of boxes, a bending rail supporting a box blank and folding a side thereof about the form, means fixing one portion of the rail to one support, and means slidably supporting another portion of the rail on another support for endwise movement relative to such latter support.

14. In a box-staying machine, in combination, a form, stay-feeding devices, and corner pressers applying the stays to the corners of the box having a shank and a pressing head flexibly connected to such shank with capacity for swinging and twisting of the head with respect to the shank.

15. In a box-staying machine, in combination, a form, stay-feeding devices, a corner presser diagonally disposed to the sides of the form, having a head formed with a dihedral angle pressing a stay against the corner of a box supported by the form, a reciprocating shank, and flexible means connecting the head and the shank with capacity for swinging and twisting of the head with respect to the shank.

16. In a box-staying machine, in combination, a form, stay-feeding devices, a corner presser applying the stays to the corners of the box, means heating the surface of the presser which applies the stays, and means supporting and actuating the presser toward and from the box including a plurality of members attached to the presser in horizontally spaced relation leaving air-circulation passages between these several members.

17. In a box-staying machine, in combination, a form, stay-feeding devices, a corner presser applying the stays to the corners of the box having a head formed with a dihedral angle fitting the corner of the box, a shank adapted to be reciprocated toward and from the box, and

connections between the head and shank supporting and reciprocating the head comprising a plurality of spring strips disposed in vertical planes and in horizontally spaced relation and each having its ends respectively fixed to the head and to the shank.

18. In a box-staying machine, in combination, a form, thermoplastic-stay-feeding devices, heated corner pressers applying the stays to the corners of the box, supports for the corner pressers having guideways in which the corner pressers are mounted for movement toward and from the form, and on which supports the stay-feeding devices are mounted, and heat-insulating material intervening between the pressers and their guideways, whereby transfer of heat from the corner pressers to the supports and stay-feeding devices is inhibited.

19. In a box-staying machine, in combination, means setting up box blanks into box form, four corner pressers, supports for the corner pressers, a stay-feeding device serving each corner presser and mounted on the latter's support, stay-cutting means located between the stay-feeding device and its associated corner presser, shafts each driving a pair of the stay-feeding devices, driving means for the shafts, and quickly-detachable means connecting each shaft to its driving means and each stay-feeding device to its support, permitting removal and replacement of a pair of stay-feeding devices and their common driving shaft as a unit without loss of the driving relation between these parts.

20. In a box-staying machine, in combination, means setting up box blanks into box form, four corner pressers, supports for the latter, stay-feeding devices each serving one corner presser and removably mounted on the latter's support, stay-cutting blades located between each stay-feeding device and its associated corner presser, a drive shaft driving a pair of stay-feeders and mounted in the machine with capacity for removal and replacement along with its two stay-feeding devices as a unit without loss of its driving engagement with the stay-feeders and its timed relation to the other machine parts, to give access to the cutting blades.

21. In a box-staying machine, in combination, means setting up box blanks into box form, means applying stays to the box corners, a roll feeding stay material to the applying means, a second roll pressing the stay material against the feed roll, an arm carrying the second roll, and an eccentrically adjustable pivot for such arm.

22. In a box-staying machine, in combination, means setting up box blanks into box form, means applying stays to the box corners, a roll feeding stay material to the applying means, a second roll pressing the stay material against the feed roll, an arm carrying the second roll, a finger on such arm engaging the stay material after the latter emerges from between the rolls and directing it substantially vertically downward and an eccentrically adjustable pivot for such arm.

23. In a box-staying machine, in combination, means setting up the boxes and applying stay strips to the corners thereof, stay-feeding devices, actuating means for the latter including an eccentric, and means varying the throw of the eccentric including an element rotatable coaxially with the eccentric's orbit and itself having an eccentrically located pin moving the ec-

centric toward and from the axis of the latter's orbit.

24. In a box-staying machine, in combination, means setting up the boxes and applying stay strips to the corners thereof, stay-feeding devices, actuating means for the latter including an eccentric, and means varying the throw of the eccentric including an element rotatable coaxially with the eccentric's orbit and itself having an eccentrically located pin moving the eccentric toward and from the axis of the latter's orbit, and indicating means cooperating with the said rotatable element showing the length of stay fed at the various settings of the throw of the eccentric actuating the stay-feeding devices.

25. In a box-staying machine, in combination, a form, means setting up box blanks into box shape about the form, means moistening stay material coated with water-activated adhesive and feeding it into proximity to the corners of the set-up box, pressers pressing the stay material against the corners of the box, and means heating the pressers.

26. In a box-staying machine, in combination, a form, stay-feeding devices, a metallic corner presser applying the stays to the corners of the box, means heating the surface of the presser which applies the stays, a metallic corner block in which the presser reciprocates and on which the stay-feeding devices are mounted, and means supporting and guiding the presser in its movements toward and from the box and preventing

metal-to-metal heat conduction from the heated portions of the presser at and adjacent the heated surface thereof to the corner block.

27. In a box-staying machine, in combination, a form, stay-feeding devices, a corner presser applying the stays to the corners of the box, means heating the surface of the presser which applies the stays, a corner block in which the presser reciprocates and on which the stay-feeding devices are mounted, and means supporting and guiding the presser in its movements toward and from the box and keeping the heated portions of the presser from heat-transmitting contact with the corner block.

15

CLAYTON STRAW.
